HYDRAULIC PRESS

Albert R. Pratt, West Newton, and Rocco Oppedisano, Arlington, Mass., assignors to Apro Engineering, Inc., West Newton, Mass., a corporation of Massachusetts

Filed May 27, 1963, Ser. No. 75,067

Term of patent 14 years

(Cl. D63—1)

FIG. 1

FIG. 5

FIG. 2

FIG. 3

FIG. 4

FIG. 1 is a perspective view of a hydraulic press showing our new design;

FIG. 2 is an end view thereof, looking from the left with respect to FIG. 1;

FIG. 3 is a front elevational view thereof, it being understood that our press has the same appearance at its rear side;

FIG. 4 is a top view thereof; and

FIG. 5 is a view showing the end opposite that shown in FIG. 2.

We claim:

The ornamental design for a hydraulic press, substantially as shown and described.
